Primary Examiner — Mitchell Siegel(74) *Attorney, Agent, or Firm* — Tomlinson McKinstry, P.C.(57) **CLAIM**

The ornamental design for control panel bars, as shown and described.

DESCRIPTION

FIG. 1 is a top plan view of the control panel bars of our new design;

FIG. 2 is an enlarged top plan view thereof;

FIG. 3 is a rear elevation view of FIG. 1;

FIG. 4 is an enlarged view of FIG. 3; and,

FIG. 5 is a perspective view.

The broken line showing is included for the purpose of illustrating and forms no part of the claimed design.
